5,504.

To all whom it may concern:

Be it known that we, CHRISTIAN BODMER and ROBERT N. PECK, citizens of the United States, residing at New Britain, county of Hartford, State of Connecticut, have invented certain new and useful improvements in Hinge-Butt and Mortise Gages, of which the following is a full, clear, and exact description.

10 Our invention relates to improvements in carpenters' tools and particularly to so called hinge and butt gages.

The object of the invention is to improve the construction set forth in a copending application, No. 486,997, filed by

Our invention relates to improvements in carpenters' tools and particularly to so-called hinge and butt gages. The object of the invention is to improve the construction set forth in a copending application, Serial No. 486,997, filed by one of the applicants herein. The present invention aims at providing a gage of a character described as follows: which is a full, clear, act description.

ences by which great advantages are ob-
tained, a cage body having a central well
of which are parallel and
of which are resp-
onding to

ences by which great advantages are obtained. 1 is the gage body having a central web portion, the ends of which are parallel and the sides and edges of which are respectively parallel and at right angles to the plane of the ends. One end is provided with a projecting bearing flange 2, the function of which will be hereinafter explained. This feature is one of the additional features to those set forth in the former application. 4 are cutter bars adjustably mounted in axial bores or guideways in the body 3 (see Fig. 3) with cutters 5 of di-

In this view
bar a

In said body for 105
respectively of said bar, said
having a slot entering said body to afford
sage from one edge of said cutters, said body 110
clearance for one of said cutters, said side of
having a channel on the opposite side of
said guide for the other cutter, said cutter
clearance for the other cutter being reversible both
bar with its cutter being arranged 115
axially and end for end and being arranged
to pass through said gage body and in any of its
to end in either direction and in any of its
adjusted positions said cutter bar being ar-
ranged to project one of its cutters beyond
the end of said body. 120

3. In a gage, a body, a cutter bar carried
thereby, said body having a guide passage for
having supplemental clearance passages for
cutters projecting laterally from the bar
ends, two cutters one on each end of said 125
bar and projecting laterally from the bar
opposite directions, one of said supple-
mental clearance passages constituting a slot
intersecting one edge of the body and ex-
tending from end to end thereof, one of said 130

- cutters being of sufficient length to project through said slot and to stand slightly above the plane of said edge, and a laterally projecting bearing flange at one end of said body adjacent to said slotted edge. 5
4. In a gage, a body having parallel sides and edges respectively and parallel ends square with respect to said sides, an integral side offset at one end of the body and squared along its inner edge relatively to the axis of said body, a flanged offset from one end of said body and adjacent to one edge of said body and squared on its outer edge adjacent to the end and relatively to 10 the axis of said body, and a coöperating cutter device adjustably carried by said body the cutter part of said cutter device being arranged to be projected beyond the end of said body. 15
- 20 5. In a gage, a body having two parallel end bearings, two parallel side bearings, two parallel edge bearings and a laterally projecting integral inside squaring flange at one side of said body at one end thereof and a laterally projecting outside squaring flange at one end of said body, and a cutter device 25 adjustably carried by said gage body and movable longitudinally relatively thereto.
6. In a gage, a body having two parallel end bearings, two parallel side bearings, two parallel edge bearings and a laterally projecting inside squaring flange at one side of said body, and a laterally projecting outside squaring flange at one edge of said 30
- body, said body also having a guide passage for a cutter bar and a cutter bar adjustable in said guide passage, two oppositely laterally projecting cutters at the ends of said bar respectively, said cutter bar and cutters being reversible in said gage body. 35
7. In a gage, a body having two parallel end bearings, two parallel side bearings, two parallel edge bearings and a laterally projecting inside squaring flange at one side of said body and a laterally projecting integral outside squaring flange at one edge of said body at the end thereof, and two parallel cutter devices adjustably carried by said gage body and movable longitudinally 40 relatively thereto. 45
8. In a butt gage, a removable and reversible cutter bar, a cutter at each end thereof, said cutters projecting laterally from said bar in opposite directions, one of said cutters being longer than the other, and a body 50 having a guide passage for said cutter bar, said body having a slot entering said guide passage from one edge and having a channel at the opposite side of said passage, said slot and channel being sufficiently large to afford clearance for said laterally projecting cutters when said bar is moved end wise in either direction. 55
